(57) **CLAIM**

The ornamental design for a body of a digital single-lens reflex camera, as shown and described.

DESCRIPTION

FIG. 1 is a front, top and right side perspective view of a body of a digital single-lens reflex camera, showing my new design;

FIG. 2 is a rear, top and left side perspective view thereof; FIG. 3 is a rear perspective view thereof with the cover of the back display in an opened and rotated state;

FIG. 4 is a front elevational view thereof;

FIG. 5 is a rear elevational view thereof; and

FIG. 6 is a top plan view thereof.

FIG. 7 is a bottom plan view thereof;

FIG. 8 is a right side elevational view thereof; and,

FIG. 9 is a left side elevational view thereof.
